(57) **CLAIM**

The ornamental design for an LED troffer as shown and described.

DESCRIPTION

FIG. 1 is a front, perspective view of the first embodiment of an LED troffer showing our new designs;

FIG. 2 is a front view of the first embodiment of an LED troffer;

FIG. 3 is a rear view of the first embodiment of an LED troffer;

FIG. 4 is a left side view of the first embodiment of an LED troffer;

FIG. 5 is a right side view of the first embodiment of an LED troffer;

FIG. 6 is a top plan view of the first embodiment of an LED troffer;

FIG. 7 is a bottom plan view of the first embodiment of an LED troffer;

FIG. 8 is a front, perspective view of the second embodiment of an LED troffer showing our new designs;

FIG. 9 is a front view of the second embodiment of an LED troffer;

FIG. 10 is a rear view of the second embodiment of an LED troffer;

FIG. 11 is a left side view of the second embodiment of an LED troffer;

FIG. 12 is a right side view of the second embodiment of an LED troffer;

FIG. 13 is a top plan view of the second embodiment of an LED troffer; and,

FIG. 14 is a bottom plan view of the second embodiment of an LED troffer.
